UNITED STATES PATENT OFFICE.

BENJAMIN C. BRADLEY, OF ALLIANCE, OHIO.

DESIGN FOR A TRAY.

SPECIFICATION forming part of Design No. 30,435, dated March 28, 1899.

Application filed March 3, 1899. Serial No. 707,872. Term of patent 7 years.

To all whom it may concern:

Be it known that I, BENJAMIN C. BRADLEY, a citizen of the United States, residing at Alliance, in the county of Stark and State of Ohio, have invented and produced a new and original Design for Trays, of which the following is a specification, reference being had to the accompanying drawings, forming part thereof.

- 10 Figure 1 is a perspective view. Fig. 2 is a top view.

As shown in the drawings, the leading or material feature of my design consists in a triangular tray provided with the bottom 1 and the sides 2 and the end 3. The sides 2 15 are curved upward toward the vertex 4, said curvature increasing from the points 5. The flange 3 is also curved, or, in other words, is

formed rounding between the vertexes 6. The flanges 2 and 3 are formed straight upon 20 their bottom or under edges and are all in substantially the same plane, as illustrated in Fig. 1.

Having fully described my invention, what I claim as new, and desire to secure by Letters 25 Patent, is—

The design for a tray as herein shown and described.

In testimony that I claim the above I have hereunto subscribed my name in the presence 30 of two witnesses.

BENJAMIN C. BRADLEY.
